ROTARY VENTILATOR

Edward P. Mattke, Milwaukee, Wis., assignor to Loeffelholz Company, Milwaukee, Wis., a corporation of Wisconsin

Application July 14, 1954, Serial No. 31,423

Term of patent 14 years

(Cl. D62—3)

Fig. 1.

Fig. 2.

Figure 1 is a perspective view of a rotary ventilator embodying my new design, showing the front and one side thereof; and

Figure 2 is a perspective of the ventilator viewing it from the opposite back corner.

I claim:

The ornamental design for a rotary ventilator, as shown.
